UNITED STATES PATENT OFFICE

2,626,475

CARTRIDGE CARRIER FOR REPEATING SHOTGUNS

Val A. Browning, Ogden, Utah

Application April 13, 1948, Serial No. 20,739

8 Claims. (Cl. 42—17)

1

This invention relates to shotguns of the type having a barrel, a breech block adapted to recoil upon firing of the gun, and a carrier for transferring a shell from a position below the line of the barrel to a position aligned with the barrel and from which position the shell is carried by the breech block into the firing chamber as the breech block is moved to breech closing position.

An object of the invention is to provide a new and improved arrangement of a shell transfer carrier and means for operating the same, the arrangement being characterized by its simplicity in construction, its economy in manufacture and its effectiveness of operation.

A further object of the invention is to provide an improved shotgun particularly adapted to take care of two shots in succession and which may be manually loaded in a very simple and easy manner.

A still further aim of the invention is to provide a shotgun of this type whereby a shell, of any length within recognized standards, may be manually positioned upon the carrier by merely inserting the shell through a loading opening in the side of the receiver. With my improved arrangement, if no shell is in the gun, the first shell, when positioned on the carrier, is immediately transferred by the carrier to a position where the breech block (the same having been released from recoil position by the insertion of the shell) moves the shell into the firing chamber of the barrel. One shell having been thus positioned, the second shell may now be placed upon the carrier by inserting the shell through said opening and this second shell is maintained upon the carrier and against any likelihood of it being thrown out through the loading opening upon recoil of the gun. When the first shell is fired, the shell on the carrier is lifted to a position where the breech block on its forward movement will feed the same into the firing chamber. A particular advantage of my improved arrangement is that each shell may be placed upon the carrier and will be properly maintained thereon without the necessity of doing otherwise than inserting the shell itself, the use of closures for the loading opening in order to prevent the shell from being kicked out of place being eliminated.

While I have shown in the present illustrative disclosure the improvements of the present invention applied to a two shot gun, it is to be understood that certain of my improvements are not limited, in application, thereto.

Other objects will be in part obvious and in part pointed out more in detail hereinafter.

2

The invention accordingly consists in the features of construction, combination of elements and arrangement of parts which will be exemplified in the construction hereafter set forth and the scope of the application of which will be indicated in the appended claims.

The following description will be more readily understood by reference to the accompanying drawings in which similar reference numerals refer to similar parts and in which

Figure 1 is a sectional view taken longitudinally and vertically through a firearm in which one embodiment of the present invention is incorporated;

Fig. 2 is a sectional view taken horizontally through the firearm;

Fig. 3 is a side, elevational view thereof; and

Fig. 4 is a cross-sectional view taken on line 4—4 of Fig. 3 and looking in the direction of the arrows.

Referring to the drawings in detail, the firearm shown has a frame or receiver 10, a barrel 11, and a stock 12. The rear end of the barrel, which is conventionally shown as being in the form of a barrel extension 13, is slidably mounted in an opening in the forward end of the receiver. The receiver has the usual ejection opening 14. Secured to the forward end of the receiver and disposed beneath the barrel is a guide 15 for the recoil spring 16. Within the receiver is a breech block 20 which may be of any suitable construction, the same being shown more or less conventionally in the drawings. Pivoted to the breech block is a locking block having a rearwardly facing shoulder adapted to engage a locking shoulder in the barrel extension for locking the breech block to the barrel extension so that the same will recoil in unison upon firing of a shell. The breech block is urged forwardly to its breech closing position by means of an action spring 21 located within the stock. This action spring bears against a guide piece 22. Pivoted to the locking block is a link 23, the rear end of which bears against the guide piece. About the guide is a recoil spring 16. The arrangement so far described is embodied generally in the firearm disclosed in my pending application Serial No. 560,744 filed October 28, 1944, now Patent No. 2,480,074. With respect to the operation of the parts described, it is here sufficient to say that, upon firing of a shell, the barrel and breech block, due to the force of explosion, will recoil and the recoil movement of the barrel is retarded and stopped whereupon the breech block is disengaged from the barrel and will continue to recoil, and during the continuing recoiling move-

ment of the breech block, the barrel will be advanced by the recoil spring to firing position. The action spring will then return the breech block to breech closing position with respect to the barrel which has already been brought to firing position.

The firearm will, of course, be provided with a suitable firing mechanism, the same being shown more or less diagrammatically in the drawings. This mechanism includes a trigger plate 25 located in the lower rear corner of the receiver, a trigger 26, and a hammer 27.

In accordance with the present invention, the receiver has a loading opening 30 in its side wall, and disposed below the ejection opening and within the receiver is a carrier 31 having a shell receiving or supporting portion 32 which is normally disposed in a position to receive a shell inserted through the loading opening. The carrier has a pair of arms 33 extending rearwardly from the shell receiving portion, these arms being in straddling relation to the firing mechanism and being pivoted between their ends to the trigger plate. In the present illustrative disclosure, the arms of the carrier are pivoted by means of pivot pins 34 to lugs or ribs 35 extending upwardly from the trigger plate. Along that side of the shelf 32 which is opposite the loading opening is an upstanding flange 36 for laterally limiting the extent to which the shell may be inserted into position on the carrier. This flange, adjacent its upper forward end, is inclined rearwardly and upwardly as at 37 and then downwardly and rearwardly at 38 so that the same may properly cooperate with the breech block, as later described. Carried by the rear ends of the arms of the carrier is a locking dog 40 for locking the breech block in approximately its rearmost recoiled position. The link has an abutment 41 which cooperates with this dog. The dog is normally urged into breech block holding position and the carrier is normally urged towards shell delivering position by a spring 42, this arrangement being generally similar to that shown in my said pending application.

The numeral 45 designates a carrier latch pivotally mounted in a recess 46 in the wall of the receiver opposite the loading opening and normally urged into its latching position with respect to the carrier by a leaf spring 47. The carrier latch, adjacent its rear end, has an edge 48 which is adapted to overlie and engage an edge 49 on the flange of the carrier in order to hold the latter in down position after the last shot is fired or there is no shell on the carrier. The rear edge 50 of the latch is adapted to engage in front of the rim of the shell so as to hold the shell against accidental displacement and at this time the shell holds the carrier latch out of the path of movement of the carrier. At the rear end of the loading opening 30 is a lip 51 having a rearwardly facing shoulder 52 which is laterally aligned with the rear edge 50 of the carrier latch so that this shoulder and that edge cooperate to hold the properly inserted shell against accidental displacement. The carrier latch is provided with a button 53 by means of which it may be released from the carrier, this being done particularly when it is desired to manually close the action. In order to assist in the manual loading of the shell on the carrier, there is provided a pusher 55 mounted for limited reciprocation in the rearward end of the guide and normally urged rearwardly by a relatively light spring 56 within the guide. The forward edge 57 of the trigger plate

constitutes a rearward stop against which the head of the shell engages.

The operation will now be briefly described and, as a starting point, it may be assumed that there is no shell in the gun and that the breech block is held in its retracted position by the locking dog 40, a condition which it assumed when the last previous shot has been fired. A shell may now be inserted through the loading opening 30 by placing the shell in the inclined position shown by dotted lines in Fig. 2 with its forward end in the receiving opening and against the pusher 55 and then moving the shell forwardly to compress the pusher spring until the head of the shell clears the rear end of the loading opening and then pushing the rear end of the shell laterally into position. Such manual loading will cause the head of the shell to press the carrier latch out of the path of the carrier which latter will thereupon spring upward carrying the shell into position to be loaded into the firing chamber. The breech block being thus released will snap forward and move the shell into the firing chamber. As the breech block moves forwardly to its breech closing position, the lower edge thereof wipes against the edge 38 of the flange of the carrier so that the latter is cammed or forced down to its shell receiving position whereupon the carrier latch will move into latching position therewith. Another shell may now be inserted through the loading opening and onto the carrier in the manner previously described but, in this instance, while the carrier latch is released, the breech block, due to its engagement with the flange of the carrier, will hold the carrier down, and the head of the shell will engage and be maintained in engaged position behind the rear edge of the latch and the shoulder 52 of the lip. Upon firing of the shell in the firing chamber, the barrel and breech block will recoil in unison until rearward movement of the barrel is stopped by the recoil spring, and then the breech block will continue to recoil and during such movement the spent shell is extracted from the firing chamber and ejected through the ejection opening in the usual manner by a suitable extractor and ejector. During the recoil movement of the breech block, after the recoil movement of the barrel has been stopped, the carrier is retained in down position because of the engagement of the flange 36 against the bottom of the advancing barrel extension, and while the flange is so engaged, the breech block reaches its rearmost position and the dog 40 engages the shoulder 41 on the link, thereby locking the breech block back. As the barrel approaches its firing position, the barrel extension moves out of engagement with the flange 36 of the carrier, whereupon the carrier, under the influence of the reaction spring and the spring 42, is raised to a position where the shell thereon is in line with the firing chamber and, of course, the line of movement of the breech block. The breech block, when the carrier is thus raised, is released from its rearmost position and, therefore, under the influence of the action spring, moves forwardly and forces the raised shell into the shell chamber of the barrel. This sequence of operation is repeated after a shot as long as fresh shells are loaded into the loading opening. If both shots are fired, the carrier latch comes into operation and the mechanism remains open, the parts now being in the same position as described at a starting point.

As many changes could be made in the above construction and many apparently widely differ-

ent embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. In a firearm, a receiver, a barrel extending forwardly therefrom, a breech block mounted for reciprocation in the receiver behind the barrel, said receiver having a loading chamber beneath the breech block, a carrier mounted for movement in said chamber between a depressed cartridge receiving position and an elevated position where it holds the cartridge thereon in alignment with the barrel, said receiver having in one of its side walls a loading opening through which a cartridge may be inserted into said chamber and onto said carrier when the latter is in depressed position, and a rearwardly facing shoulder in said receiver adjacent the rear end of said opening and behind which the rim of the cartridge is adapted to engage when properly positioned upon the carrier.

2. In a firearm, a receiver, a barrel extending forwardly therefrom, a breech block mounted for reciprocation in the receiver behind the barrel, said receiver having a loading chamber beneath the breech block, a carrier mounted for movement in said chamber between a depressed cartridge receiving position and an elevated position where it holds the cartridge thereon in alignment with the barrel, said receiver having in one of its side walls a loading opening through which a cartridge may be inserted into said chamber and directly positioned onto said carrier when the latter is in depressed position, and a carrier latch having a rear end adapted to overlie a portion of the carrier to hold the same in depressed position when a cartridge is not on the carrier, the rear end of said carrier latch constituting an abutment behind which the rim of the cartridge is adapted to engage when the latter is positioned upon the carrier whereby the cartridge is held against accidental movement with respect to the carrier.

3. In a firearm, a receiver, a barrel extending forwardly therefrom, a breech block mounted for reciprocation in the receiver behind the barrel, said receiver having a loading chamber beneath the breech block, a carrier mounted for movement in said chamber between a depressed cartridge receiving position and an elevated position where it holds the cartridge thereon in alignment with the barrel, said receiver having in one of its side walls a loading opening through which a cartridge may be inserted into said chamber and onto said carrier when the latter is in depressed position, and a carrier latch having a rear end arranged to overlie a portion of the carrier when the latter is in depressed position and no cartridge is upon the carrier, a forwardly facing fixed shoulder in the receiver and against which the head of the cartridge is adapted to engage for limiting rearward movement of the cartridge, the rear end of said carrier latch constituting a rearwardly facing shoulder behind which the flange of the cartridge is adapted to engage when the cartridge is positioned upon the carrier, and

7
spring means urging said carrier latch inwardly of the receiver.

4. In a firearm, a receiver, a barrel extending forwardly therefrom, a breech block mounted for reciprocation in the receiver behind the barrel, said receiver having a loading chamber beneath the breech block, a carrier mounted for movement in said chamber between a depressed cartridge receiving position and an elevated position where it holds the cartridge thereon in alignment with the barrel, said receiver having in one of its side walls a loading opening through which a cartridge may be inserted into said chamber and onto said carrier when the latter is in depressed position, and a rearwardly facing fixed shoulder on the wall in said loading opening and located adjacent the rear end of said opening and behind which the flange of a cartridge is adapted to engage when positioned upon the carrier.

5. In a firearm, a receiver provided with side walls, a barrel carried by the receiver, a breech block mounted for reciprocation in the receiver, a carrier mounted between the side walls of the receiver and below said breech block and having a cartridge receiving portion mounted for movement between a depressed cartridge receiving position and an elevated position, one of the side walls of said receiver having a loading opening through which a cartridge may be passed onto said cartridge receiving portion of the carrier when the latter is in depressed position, a carrier latch opposite said loading opening and arranged to overlie the cartridge receiving portion of the carrier when the latter is in depressed position, and an abutment on the first mentioned wall of the receiver adjacent the rear end of said loading opening and behind which the flange of a cartridge is adapted to engage when positioned upon the carrier, said carrier latch having at its rear end an abutment laterally aligned with said first mentioned abutment and behind which the flange of the cartridge is adapted to engage.

6. In a firearm, a receiver, a barrel extending forwardly therefrom, a breech block mounted for reciprocation in the receiver behind the barrel, said receiver having a loading chamber beneath the line of movement of the breech block, a carrier mounted for movement in said chamber between a depressed cartridge receiving position and an elevated position, said receiver having in one of its side walls a loading opening through which a cartridge may be inserted into said chamber and onto said carrier when the latter is in depressed position, a rearwardly facing shoulder in said receiver adjacent the rear end of said opening and behind which the rim of the cartridge is adapted to engage when positioned upon the carrier, and a rearwardly sprung plunger at the forward end of said chamber and arranged to urge a cartridge on the carrier rearwardly to a position where the flange of the cartridge engages behind said abutment.

7. In a firearm, a receiver provided with side walls, a barrel carried by the receiver, a breech block mounted for reciprocation in the receiver, a carrier mounted between the side walls of the receiver and below said breech block and having a cartridge receiving portion mounted for movement between a depressed receiving position and an elevated position, one of the side walls of said receiver having a loading opening through which a cartridge may be passed onto said cartridge receiving portion of the carrier when the latter is in depressed position, a carrier latch opposite said loading opening and arranged to overlie the

cartridge receiving portion of the carrier when the latter is in depressed position, an abutment on the first mentioned wall of the receiver adjacent the rear end of said loading opening and behind which the flange of a cartridge is adapted to engage when positioned upon the carrier, said carrier latch having at its rear end an abutment laterally aligned with said first mentioned abutment and behind which the flange of the cartridge is adapted to engage, and a rearwardly spring pressed plunger at the forward end of said chamber and arranged to urge the cartridge rearwardly so as to engage the flange of the shell behind said abutments.

8. In a firearm, a receiver, a barrel, a breech block mounted for reciprocation, said receiver having a chamber below the breech block, a pivoted carrier mounted in the receiver below the breech block and having a cartridge-receiving portion, said receiver having a loading opening in one of its side walls and adjacent said cartridge-receiving portion of the carrier, said cartridge-receiving portion having on the side thereof of opposite said loading opening an upstanding flange against which a shell is adapted to engage, the upper edge of said flange being adapted to engage said breech block whereby the carrier is moved downwardly to depressed position as the breech block moves forwardly and is held in said position by the breech block when the 30

breech block is in breech closing position, a spring constantly urging said carrier towards its elevated position, interengaging means between the carrier and breech block releasably maintaining the latter in retracted position after firing the last cartridge in the firearm, and a carrier latch for releasably maintaining the carrier in cartridge-receiving position and movable to unlatching position by a cartridge when the same is positioned upon the carrier.
